CLAIM

The ornamental design for a bottle for oil, as shown and
described.

DESCRIPTION

FIG. 1 is a side elevation of a bottle for oil, the opposite
side is a mirror image thereof except for the conventional
screw threading on the neck;

FIG. 2 is a top view;

FIG. 3 is an isometric view of one end thereof;

FIG. 4 is an end elevation as seen from the left of FIG.

1; and,

FIG. 5 is an end elevation as seen from the right of FIG.

1.

FIG. 1

FIG. 2

FIG. 3

FIG. 5
